UNITED STATES PATENT OFFICE.

LEE R. LOWTHER, OF CARDINGTON, OHIO.

BALING-PRESS.

1,319,596.

Specification of Letters Patent.

Patented Oct. 21, 1919.

Application filed March 14, 1918, Serial No. 222,417.

To all whom it may concern:

Be it known that I, LEE R. LOWTHER, a citizen of the United States, and a resident of Cardington, in the county of Morrow and State of Ohio, have invented a certain new and useful Improvement in Baling-Presses, of which the following is a specification.

This invention relates to baling apparatus and more particularly to an apparatus for 10 pressing a bale into the desired form and properly binding it with tie wires by suitable mechanism which is practically automatic in operation and in synchronism with the various operative portions of the apparatus which go to make up the complete 15 device.

The invention has for one of its objects to provide a baling press in which the material to be formed into a bale is fed into position 20 to be readily acted upon by suitable compressing mechanism so associated with the feeding device that an intermittent feeding and compressing action occurs during the 25 baling process.

In the preferred embodiment of the present invention, a twisting mechanism is employed for twisting the tie wires at the desired point whereby the binding wires are tied together at the exact center of the ends 30 of the bales where the knotted portions may be bent or compressed to further reinforce the knots and thereby prevent slack occurring in the binding wires thereby preventing bowed or improperly shaped bales.

Suitable timing and tie regulating mechanism is included in the apparatus, and the various mechanisms and devices are properly associated with each other so that the entire apparatus is practically automatic in its 40 operation and thereby assures greater speed in the forming and tying of bales.

Various other objects will appear upon reference to the following detailed description and the accompanying drawings 45 wherein:

Figure 1 is an elevation of one side of the apparatus.

Fig. 2 is an elevation of the opposite side.

Fig. 3 is a top plan view.

Fig. 4 is a longitudinal horizontal section.

Fig. 5 is a longitudinal vertical section, some of the parts being eliminated to more clearly illustrate the tucking and compressing mechanism.

Fig. 6 is a section taken substantially on 55 the line 6—6 of Fig. 3.

Fig. 7 is a transverse section taken on the line 7—7 of Fig. 4 to illustrate the laterally movable wire carriages.

Fig. 8 is a slightly enlarged fragmentary 60 elevation of a portion of the mechanism illustrated in Fig. 1.

Fig. 9 is a section taken substantially on the line 9—9 of Fig. 8.

Fig. 10 is a detail perspective of one of 65 the elements illustrated in Fig. 8.

Fig. 11 is a detail perspective of a part of the invention.

Fig. 12 is a detail perspective of one of the wire twisting gears.

Fig. 13 is a perspective view of one of the knives.

Fig. 14 is a perspective view of one end of one of the wire carrying carriages.

Fig. 15 is a perspective view of a detail 75 of the invention.

Fig. 16 is a section through the upper end of one of the carriages illustrating the manner of associating the gears and cutting knives.

Fig. 17 is a detail view of a portion of the invention.

Fig. 18 is a detail view of the manner in which the wires are twisted for tying the bales and forming the ends thereof.

Fig. 19 is an enlarged view of the tie timing regulator showing the mechanism in side elevation.

Fig. 20 is a plan view of the same.

Fig. 21 is a perspective view of a portion 90 of the mechanism shown in Figs. 19 and 20.

Fig. 22 is a cross section taken substantially on the line 22—22 of Fig. 4.

Fig. 23 is a detail view of one of the operating levers.

Fig. 24 is a detail view of one of the levers employed in the time regulator.

Fig. 25 is an enlarged view of one of the locking devices.

Referring to these drawings, wherein is 100 illustrated the preferred form of my invention and in which like numerals of reference indicate the corresponding parts throughout the several views, the main frame 1 is mounted upon bolsters which are supported 105 by wheels 2 to provide a portable device which may be moved from place to place as desired. The frame is constructed to pro-

vide an elongated interior space one end of which forms a baling chamber 3 while intermediate the ends of this space is a receiving compartment 4 into which the hay or other material to be formed into a bale is deposited. A drive shaft 5 is mounted upon the frame near one end thereof and has its ends journaled in a supporting bracket 6 the terminals of which are disposed on opposite sides of the frame as indicated clearly in Fig. 3 of the drawing. One end of the shaft 5 carries a drive pulley 6' over which a belt may be passed to drive the shaft from a suitable source of power such as a motor or engine. At the opposite side of the frame, the shaft carries a balance wheel 7 and this shaft also carries a pinion 8 in mesh with a large gear 9 on a counter-shaft 10 and this counter-shaft carries drive pinions 11 at the ends of the shaft, each of which meshes with the large gears 12 mounted upon stud shafts 13. Extending laterally between the two gears 12 and having its ends attached thereto is a crank pin 14 connected to one end of a pitman 15 the opposite end of which is pivotally joined to the compressor head 16 movable into and out of the receiving compartment 4 and also partially into and out of the baling chamber 3. This compressor head 16 is provided with laterally projecting guides 17 movable in guideways 18 formed in the frame. The pitman 15 is longitudinally slotted and this slot receives the curved end 19 of a pivoted yoke 20 shown in detail in Fig. 15 of the drawing. This yoke is mounted upon the shaft 5 and the curved end of the yoke is provided with an arcuate slot 21 to receive a roller 22 carried by a pin the ends of which are fixed in the pitman at opposite sides of the slots. Pivotally mounted on the shaft 5 at opposite sides of the yoke 20 is a curved arm 23 and these arms carry a feeding head 24 which is rigidly secured to the arms and is movable into and out of the receiving compartment when the arms are raised and lowered. Attached to each of the arms 23 is a coil tension spring 25 the opposite end of which is joined to a lug 26 formed on the yoke 20, as shown in Fig. 15. When the pitman 15 is reciprocated, the yoke 20 will be swung on its pivot and will oscillate as long as the motion is imparted to it through the medium of the connection established by the roller 22. As the yoke 20 oscillates, the arms 23, carrying the feeder head, will also be raised and lowered thereby moving the feeder head into and out of the receiving compartment. To prevent too great strain occurring on the feeder head, however, when the compartment is partially filled with material, the tension springs 25 act to permit a complete movement of the yokes but will permit the feeder head to stop by the resistance offered by

the material in the compartment thereby preventing injury to the parts but at the same time sufficiently thrusting the material into the compartment to accomplish the desired result.

Mounted upon one end of the frame are the wire reels or spools 26 and the wires 27 are extended longitudinally within the frame at opposite sides thereof, the spools being arranged to cause the wires at opposite sides to be disposed in superposed relation and properly spaced apart to engage the bale at the desired point. These wires are adapted to be engaged by laterally movable carriages 28 and 29, each of which is slidably mounted in a casing 30 projecting from each side of the frame at points near the entrance to the baling chamber 3 as shown in Fig. 4 of the drawing. The carriage 28 comprises a gear housing 31 including a pair of complementary members 32 held together by bolts 33 provided with recesses 34 on proximate surfaces each of which receives a bevel gear 35. As shown to advantage in Fig. 16 of the drawing, each gear 35 has its hub projected through a central opening in one of the complementary members 32 thereby suitably mounting the gear and permitting it to revolve in the recess 34. Each gear 35 is provided with a radial slot 36 and the complementary members 32 which form the gear housing are also slotted as indicated at 37. The wires at one side of the frame are arranged to pass through the center of each gear so that as the gears are rotated the wires will be twisted. In mesh with the gears are the pinions 38 carried by the ends of the shafts 39 which are equally vertically spaced apart and are simultaneously rotated by a chain drive including a drive sprocket 40 carrying a chain which also engages smaller sprockets 41 carried by the shafts 39. The drive sprocket 40 is mounted upon a shaft 42 the end of which is revolvably supported in a bracket 43. The intermediate portion of this shaft is square. The bracket 43 is attached to one of the casings 30 and this bracket also carries a guard 44 which embraces a portion of the sprocket 40 so that the carriage including the sprocket and chain, bracket and guard may be moved toward the frame to force the carriage into the end of the bale chamber.

The other carriage 29 is also mounted to move laterally into the bale chamber and includes the supporting structure which carries a plurality of fingers 45 arranged in superposed pairs and provided with notches 46 at their ends adapted to be moved into registration with the centers of the gears 35 when the two carriages are moved toward each other and into the end of the baling chamber 3. In this manner the wires from the spools are moved toward the ex-

act center of the chamber at which time the gears are rotated to twist the wires so that the twist is formed at the exact center of the end of the bale.

- 5 As shown to advantage in Figs. 12, 13 and 16, the gears 35 are adapted to carry the knives 47. Each knife consists of a substantially frusto-conical member having a longitudinal slit 48 which extends radially 10 across the end 49 to form the V-shaped cutting space 50. The edges are thereby formed to perform the cutting operation. The base of the member 47 is provided with a flange 51 having diametrically opposite arcuate slots 15 52 adapted to receive fastening pins received in the openings 53 formed in each of the gears 35. The ends of the knives in each pair are in close proximity as will be observed in Fig. 16 and the cutting edges are 20 thereby adapted to act on the center of the twisted portion of the wire so that the twisted portion will be severed at the point indicated at 53 in Fig. 18 of the drawing. The arcuate slots 52 permit the knives to be 25 properly adjusted so that the cutting will occur at the proper time and these knives also serve to maintain the gears in properly spaced relation since the proximate ends of the knives are practically in engagement as 30 will be observed in Fig. 16 of the drawing. After the tie is made, and the carriages have been backed out of the baling chamber, upon the approach of the compressor head 16, the wire is pressed back against the finished 35 bale thereby crushing and bending the twisted ends to provide a more effective knotted portion for preventing disconnection of the fastened ends of the wires. It should be noted that the ties are formed in the exact 40 center and not over the side or corner of the bale, thereby causing an even tension to be maintained on all sides of the bale to properly hold the material in the desired shape.
- The carriages 28 and 29 are moved into 45 and out of the baling chamber through the medium of levers 54 arranged at one side of the apparatus and a lever 55 on the opposite side thereof. The levers 54 are connected to a shaft 56 supported in bearings 50 57 and the opposite ends of the levers are so connected to the carriage, as shown to advantage in Fig. 7, that when the shaft is rotated, the carriage 28 is moved into the center of the baling chamber. The bracket 55 43 and the sprocket 40, of course, slide along the square shaft and the guard is provided for the purpose of maintaining the gears and chain in proper relation. The opposite lever 55, used for moving the other carriage 60 29, is connected to the shaft 53 supported by bearings 59 and this lever 55 is joined to the carriage through the medium of a pin 60 movable through a slot 60', one of which is provided in each of the levers 54 65 and 55.
- Operating levers 61 are attached to the ends of a transverse shaft 62 one end of which carries a crank 63 connected to a reach-rod 64 the opposite end of which is joined to a lever 65 fastened to one end of 70 a shaft 66 which also extends transversely across the frame 1. The shaft 66 carries a projection 67 to which is connected one end of a coil tension spring 68 having its opposite ends fastened as at 69 to a portion 75 of the frame. This spring normally urges the levers 61 into upright normal position when the operator releases his hold on either one of the levers. This shaft 66 is also provided with a crank 70 connected to a rod 71 80 which has its opposite end joined to a side lever 72. One of these levers is arranged at each side of the machine and therefore a connection with each end of the shaft 66 is made by duplicating the crank 70 and 85 the rod 71 at each side of the frame. Each of the levers 72 is provided with a projection having its curved surface forming a cam 73, the purpose of which will presently appear. The levers 72 are mounted upon 90 the outer ends of a transverse shaft 74 mounted in the lower portion of the frame. The guides 17 carry projections 75 upon which locking latches 76 are pivoted. A shelf 77, formed on each projection 75, carries a guide rod 78 extending through a recess in the latch 76 and embraced by a coil compression spring 79 acting to urge the latch downwardly whereby the toothed end 80 will engage a longitudinally extending rack bar 81, one of which is mounted on each side of the apparatus. The rack bars 81 are movable through supports 82 fixed to the frame and the lower edge of each rack bar is provided, near the end 105 thereof, with a plurality of teeth 83. The curved end of each latch 76 is engageable with the cam 73 as the compression head is moved forwardly so that the latches will be raised out of engagement with the rack bar 110 when thus engaged with the cams 73. Each rack bar is provided with a lug 84 adapted for engagement with the toothed end of the latch 76 whereby the rack bars may be moved rearwardly when the compression 115 head is withdrawn. A transverse shaft 85 is mounted in the lower portion of the frame substantially intermediate the ends thereof and this shaft carries the segmental gears 86 the teeth of which are adapted to 120 mesh with the teeth 83 on the rack bar 81. This shaft 85 also carries at each end thereof a segmental bevel gear 87, in mesh with a segmental bevel gear 88 one of which is provided on each of shafts 56 and 58, as 125 shown to advantage in Fig. 4 of the drawing. In this connection, it should be pointed out that one of the gears 86, one of the gears 87 and one of the segmental gears 88 are sufficient to impart the desired 130

motion to the rack bars, since one may be mounted at only one side of the device. The mechanism above described is duplicated on opposite sides of the apparatus, 5 however, for the reason that any failure of either one or the other of the devices to operate will not prevent the proper operation of the associated mechanism. When these segmental gears are actuated, the 10 shafts 56 and 58 will be rotated thereby imparting to the levers 54 and 55 the proper movement to impart the necessary lateral sliding motion to the carriages 28 and 29, as above set forth.

15 As shown in Figs. 1, 8 and 9, the main driveshaft 5 has keyed thereto a flanged wheel 89 which embraces the hub portion of a sprocket wheel 90. Mounted on the hub of the flanged wheel 89 is a disk 91 20 rigidly fastened to the sprocket wheel 90 by the bolts 92 which extend across the space between the disk 91 and the adjacent side of the sprocket 90. The periphery of the flanged wheel 89 is provided with a lug 25 93 and this lug is engageable by the bill 94 of a hook 95 pivotally mounted on one of the bolts 92. The hook 95 shown in detail in Fig. 10 has one edge curved to provide a cam surface 96 adapted to be engaged by 30 a pin 97 carried by a lever 98 which is also pivotally mounted on the same bolt 92 upon which the hook is mounted. When the lever 97 is actuated, the pin slides over the cam surface 96 and forces the hook 95 35 toward the center of the shaft 5 and thereby moves the bill 94 into engagement with the periphery of the flanged wheel 89 where it is engaged by the lug 93 thereby causing the disk 91 and the sprocket 90 to rotate.

40 Loosely mounted upon the shaft 5 is a ratchet wheel 99, the spokes of which are engaged by projections 100 formed on a circular guard 101 attached to the disk 91 so that as the disk is rotated, the projections, 45 being in engagement with the spokes of the ratchet wheel, will cause the latter to rotate. The lever 98 has its end connected to an arcuate connecting rod 102, the opposite end of which is joined to a lever 103 pivotally 50 mounted upon the shaft 5. The lever 103 has integrally formed with its pivoted portion the ratchet 104 adapted to be engaged by a pawl 105 carried by the rearwardly extending lever 106. One of the bolts 92 55 also carries one end of a tangentially disposed lever 107, the free end of which is engageable with a lug 108 formed on the inner periphery of the rim of the ratchet wheel 99. This lever 107 is connected by 60 a spring 109 to the projected portion 110 of the hook 95 and this hook is also shaped to form an abrupt shoulder 111 engageable with a square projecting portion on the lever 107 so that when this projection engages 65 the hook at the shoulder 111, the hook will

be held in raised position and out of engagement with the lug 93. The spring 109, however, being maintained at all times under tension, will act to draw the hook into inoperative position when the lever is disengaged from the lug 108.

70 The lever 106 has a right angularly extending end 112 from the end of which projects an extension 113 and the terminal of this projection is joined to a rod 114 connected by a coupling 115 to an arm 116 carried by the shaft 56.

75 Referring particularly to Figs. 19, 20 and 21, wherein the tie timing regulator is illustrated on an enlarged scale, it will be noted 80 that the end of the lever 106 is provided with a curved arm 117, the free end of which forms a hook 118 while the pivoted end of the lever or arm 117 carries a projection 119 to the end of which is joined a tension 85 spring 120, the opposite end of which is joined, as at 121 to a portion of the lever 106. This spring 120 acts to hold the hook 118 in releasable engagement with a small 90 lever 122 connected by a reach-rod 123 to a lever 124 suspended from a frame 125. This frame is attached to the main frame and supports the tie timing regulator. The small lever 122 is pivoted on the ratchet 95 lever 126 which is mounted on the shaft 127 and which is provided with a tooth 128 adapted to releasably engage the teeth of the ratchet wheel 99 and lock the wheel against movement until such time as the tooth 128 is released by the operation of the lever 126. 100 A pin 129 carried by the lever 126 is adapted to engage the edge of the suspended lever 124 and the latter is held in engagement with the pin by a coil spring 130. The end of the lever 124 is provided with a notch 105 131 which receives the pin 129 when the lever 126 is forced downwardly to cause the tooth 128 to turn the ratchet wheel 99.

110 The lever 124 is also provided with a projection 132 adapted to be engaged by any 110 one of the teeth in a star wheel 133 mounted on the end of a vertically disposed shaft 134. When one of the teeth in this star wheel engages the projection 132, the notch 131 will be disengaged from the pin 129, the coil 115 contractile spring 135 will immediately act to raise the lever 126 so that the tooth 128 moves into engagement with the teeth on the ratchet wheel 99 thereby instantly locking the wheel against further movement. And, 120 at the same time, the lever 107 is stopped by the lug 108 on the wheel 99. When the hook 95 is moved into engagement with the shell wheel 89, the projection 136, formed on the hook, is resting on the notch in the 125 lever 107 and the spring 109 acts to urge the hook out of engagement with the lug 93 immediately upon the projection 136 being disengaged from the notch in the lever 107.

A sprocket wheel 138 is mounted upon a stud shaft 138' carried by the frame and is driven by a chain 139. The stud shaft is also provided with a bevel pinion 140 in mesh with a large bevel gear 141 mounted upon a vertical shaft 142. The lower face of the gear 141 carries a pin 142' adapted to engage the teeth of a toothed wheel 143 mounted on the lower end of the shaft 134. 5

The teeth of the wheel 143 are also adapted to engage a dog 144 carried by a short shaft 145 as shown in detail in Fig. 21. This shaft is journaled in bearings 148' carried by a portion of the frame and between the 10 bearings 148' the shaft carries an arm 146 from which projects a finger 147 carrying a set screw 147' the end of which is adapted to engage a block 148 mounted in the frame. To hold the set screw in engagement 15 with the block, a spring 149 is provided one end of which is joined to the end of the lever 146, the opposite end being fixed to the frame. Thus it will be seen that when the wheel 143 is rotated and the teeth thereof 20 actuates the dog 144, the shaft 145 will be rotated to swing the arm 146 against the action of the spring to permit the teeth of the wheel 143 to pass over the dog. By virtue of the shape of the dog, however, and 25 also the engagement of the set screw with the block 148, the dog 144 will be prevented from moving in the opposite direction whereby locking the wheel 143 against movement in the opposite direction. By adjusting the set screw, the position of the dog 30 144 when in operative position, may be adjusted. The sprocket chain 139 passes over a sprocket 150 mounted on the uppermost of the shafts 39 and is adapted to permit 35 the shaft to slide through the opening in the center of the sprocket when the carriage 40 is moved inwardly. To maintain the sprocket 150 in the desired permanent position, however, a guard member 151 is attached to the standard in which the bearings 45 for the shaft 139 are mounted. The sprocket 150 is also provided with a clutch element 152 adapted to be engaged by a complementary clutch element 153 formed on the uppermost sprocket 41. When the carriage 50 is moved inwardly, the sprockets 41 are also moved with the carriage and therefore the two complementary clutch elements 152 and 153 will engage for causing movement to be 55 imparted to the sprocket 150 whereupon the chain will impart motion to the shaft upon which the sprocket 138 is mounted. The tie timing mechanism, therefore, is actuated when the carriages have been moved toward 60 the center of the baling chamber and the lever 126 has been pulled downwardly by the hook 118 which is in turn pulled downwardly by the turning of the shaft 56, which shaft is actuated by the segmental gears as 65 above set forth. Upon each rotation of the gear 141, the pin 142' causes a partial movement of the toothed wheel 143 since the pin engages one tooth of the wheel 143 upon each rotation of the gear 141. The size and ratio of these gear wheels, are properly worked out to cause the star wheel 143 to engage the projection on the lever 124 at the proper interval so that the lever 126 is held downwardly during the time the tie is being formed in the bale chamber. 70

The sides of the chamber are provided with entrances through which the carriages extend and these entrances are closed when the compression head is moved into the bale chamber, by swinging gates or wings 155 75 provided with slots 155' through which the wires are passed. The feeding head 24 clears the wings 155 and the wings, being hingedly mounted, are swung over to cover the entrances when the compression head is 80 moved forwardly. When the carriages are moved laterally to extend into the baling chamber, the wings 155 start to swing to open position and they remain in this position until the carriages have been withdrawn and the compression head 16 is again 85 moved forwardly. 90

A holding or retaining device is also employed in connection with the apparatus and is illustrated more particularly in Figs. 3 95 and 17 of the drawing. A catch element 156 is hingedly mounted at 157' to the top of the frame and this catch element has pivotally mounted thereon a plurality of guards 157, each of which is provided with a plurality 100 of teeth 158 which teeth are urged inwardly by contractile springs 159. Flat springs 160, attached to a cross arm 161, are engaged with the member 156 to urge the teeth of dogs downwardly and these springs are 105 engaged by the ends of the turn screws 162 screw-threadedly mounted in a cross piece 163 and adapted to be turned by a hand wheel 164. These dogs 157, through the medium of the teeth 158, hold the material 110 within the baling chamber against the back pressure occasioned by the compressed portion within the end of the baling chamber. Four retaining bars 165 are provided on 115 each side of the baling chamber which are bolted to the presser plates 166. A pressure cap 167 is mounted upon each side and is engageable with the plates 166 to maintain them under the proper tension and each of these caps is each integrally connected with 120 an adjusting screw 168. A bracket 169 is mounted upon each side of the frame, the ends of the bracket being connected to the corner pieces of the frame, as shown to advantage in Fig. 6. Directly adjacent the 125 cap 167, and pivotally mounted upon the corresponding end of each of the adjusting screws 168 is a lever 170. Each turn screw 168 also supports a ratchet wheel 171 engaged by a pawl 172 carried by each lever 130

170. The central opening in each of the ratchet wheels 171 is screw-threaded to fit the screw-threads on the adjusting screw 168, while the openings in the brackets 169 5 are large enough to prevent injury being done to the threads. The end of each screw member 168 carries a hand wheel 173 which may be moved into engagement with the brackets to lock the parts by forcing the 10 central portion of bracket into engagement with the ratchet wheel after the same has been adjusted to exert the proper pressure on the cap 167. The levers 170 are employed to tighten or loosen the caps 167 so that the 15 proper pressure may be exerted by the presser plates 166 on the sides of the bale. The top presser plate 174 is engaged by an adjusting screw 175 mounted in a bracket 176 which adjusting screw is adapted to be 20 turned by a hand wheel 177. The plate 174 is hingedly mounted on a suitable portion of the top of the frame so that the proper pressure may be exerted upon the top of the bale while the latter is being formed. 25 30 A brake shoe 178 is pivotally mounted to permit the shoe to engage the periphery of the balance wheel 7 and may be suitably connected with a convenient lever 179 for permitting the brake shoe to be operated for engaging the balance wheel to stop the machine when desired.

I claim:

1. In a baling apparatus, the combination, of a plurality of wire twisting members including radially slotted gears arranged in opposed pairs, means for rotating the gears of each pair in opposite directions, and cutters carried by the facing sides of the gears. 35
2. In a baling apparatus, the combination of a plurality of wire twisting members including radially slotted gears arranged in parallel pairs, cutters carried by the facing sides of the gears and engageable with the wire when the gears have been rotated, and 40 means for rotating the said gears.
3. In a baling apparatus, the combination of a plurality of wire twisting members including radially slotted gears, knives mounted upon the gears, the latter being 45 arranged in pairs whereby certain of the said knives are in engagement with each other, and means for rotating the said gears to simultaneously turn the gears and knives. 50
4. In a baling apparatus, the combination of laterally movable carriages, radially slotted beveled gears carried by one of the carriages and arranged in opposed pairs, means for rotating said gears, wire carrying means provided on the other carriage, and 55 means for synchronously moving the carriages toward each other. 60
5. In a baling apparatus, the combination of a pair of laterally movable carriages, radially slotted beveled gears carried by 65 one of the carriages and arranged in opposed

70 pairs, means for rotating said gears, wire carrying fingers carried by the other carriage and adapted to move into registration with the centers of the said gears when the two carriages are moved toward each other, and means for moving the carriages toward each other. 75

6. In a baling apparatus, the combination of a pair of laterally movable carriages, radially slotted gears carried by one of the said carriages and arranged in parallel pairs, knives carried by the facing sides of said gears, the latter carriage including complementary members recessed to receive the 80 said gears, means for rotating the said gears, fingers carried by the other carriage, and means for moving the said carriages and fingers into registration with the centers of the said gears. 85

7. In a baling apparatus, the combination of a pair of laterally movable carriages, radially slotted gears carried by one of the carriages, pinions supported by the carriage and in mesh with the said gears, shafting supporting the said pinions, means for imparting rotary movement to the shafting, and means for moving the said carriages toward each other, the said means and the said shafting being supported by one of the said carriages. 90 95

8. In a baling apparatus, the combination of laterally movable carriages, radially slotted beveled gears carried by one of the carriages and arranged in opposed pairs, means for rotating said gears, wire cutters 100 carried by the facing sides of the gears, means adjustably connecting the cutters to said gears, wire carrying means provided on the other carriage and means for synchronously moving the carriages toward each 105 other. 110

9. In a baling apparatus, the combination of a plurality of laterally movable carriages, a frame supporting the carriages, a plurality of radially slotted gears carried by one of the carriages, the said gears being arranged in parallel pairs, the said pairs of gears being supported in superposed relation, means for imparting rotary movement to the said gears, whereby one gear of each pair 115 will be rotated in an opposite direction to the rotation of the gear of the pair, wire carrying fingers carried by the other carriage, a lever connected to each of the said carriages, and means for swinging the said levers to laterally move the said carriages toward the center of the said frame. 120

10. In a baling apparatus, the combination of a plurality of laterally movable carriages, gears carried by one of the carriages 125 and provided with radial slots, pinions meshing with the gears, shafts supporting the said pinions, means for driving said shafts and including a pinion on one of the shafts having a complementary clutch mem- 130

ber, a second pinion on said shafts and including a second complementary clutch member adapted to register with the said first mentioned clutch member, and means 5 for moving the said carriage to carry the said first mentioned clutch member into engagement with the said second clutch member.

11. In a baling apparatus, the combination of a frame having a pair of carriages mounted therein and laterally movable through the said frame, a housing comprising complementary members supported by one of the said carriages and each provided with recesses, a slotted beveled gear mounted in each of the said recesses, means for rotating the said gears in opposite directions, fingers carried by the other carriage, and means for moving the said carriages 15 toward each other whereby the ends of the said fingers may register with the centers of the said gears at the ends of the radial slots.

12. In a baling apparatus, the combination of a frame having a pair of carriages oppositely disposed in the frame and laterally movable therethrough, a housing formed by a pair of complementary members supported by one of the said carriages, each 20 of the said members being provided with recesses and transverse slots, a beveled gear mounted in each of the said recesses and provided with a radial slot terminating at the center of the gear, the slots in said gears 25 being normally in register with the slots in the said complementary members, means for rotating the gears, and wire carrying fingers carried by the other carriage.

13. In a baling apparatus, the combination of a frame having a pair of carriages oppositely disposed in the frame and laterally movable therethrough, a housing formed by a pair of complementary members supported by one of the said carriages, 40 each of the said members being provided with recesses and transverse slots, a beveled gear mounted in each of the said recesses and provided with a radial slot terminating at the center of the gear, the slots in said 45 gears being normally in register with the slots in the said complementary members, means for rotating the gears, wire carrying fingers carried by the other carriage, and means for moving said carriages toward 50 and away from each other whereby said 55 fingers may be moved into and out of register with the ends of the said slots.

14. In a baling apparatus, the combination of a frame having a pair of carriages 60 mounted therein, disposed on opposite sides of the frame and laterally movable therethrough, a housing formed by a pair of complementary members supported by one of the said carriages, each of the said members having recesses and a transverse slot,

a beveled gear mounted in each of the said recesses, the said gears being arranged in pairs, the slots in the said gears being normally in register with the slots in the said complementary members, means for rotating 70 the gears, fingers carried by the other carriage and means for moving the said carriages toward each other whereby the ends of said fingers may register with the centers of said gears, and cutter elements carried 75 by said gears and rotatable therewith.

15. In a baling apparatus, the combination of a plurality of wire twisting members, a housing for said members, substantially conical knife members carried by 80 said twisting members, the ends of said conical knife members being normally in engagement, and means to rotate said twisting members and said knife members, the latter being arranged in pairs for co-operation with 85 each other to sever the wire when said twisting members are rotated.

16. In a baling apparatus, the combination of a plurality of wire twisting members including beveled gears arranged in 90 pairs, a housing for said gears, said housing including complementary members provided with recesses to receive said gears, a substantially conical knife member carried by each of said gears, the latter being arranged in pairs whereby two of said knife members may be disposed in close proximity, and means to rotate said gears and the said knife members simultaneously.

17. In a baling apparatus, a tying mechanism including a pair of radially slotted gears, means for rotating said gears in opposite directions, substantially frusto-conical cutters carried by the facing sides of said gears and provided with radial slots, the 105 edges of said slots in the apices of said cutters being sharpened to form cutting edges.

18. In a baling apparatus, a tying mechanism including a pair of radially slotted gears, means for rotating said gears in opposite directions, frusto-conical cutters carried by the facing sides of said gears and provided with radial slots, the edges of the slots in the apices of said cutters being sharpened 110 to form cutting edges, and means adjustably connecting said cutters to said gears.

19. In a baling apparatus, a tying mechanism including radially slotted beveled gears 115 arranged in opposed relation, a beveled pinion meshing with said gears whereby the gears will be rotated in opposite directions, frusto-conical cutters carried by the facing sides of said gears and provided with radial slots, the edges of the slots in the apices of said cutters converging toward the center of the cutter and being sharpened to form cutting edges.

20. In a baling apparatus, a tying mecha- 120

- nism including radially slotted beveled gears arranged in opposed pairs, a beveled pinion meshing with said gears whereby they will be rotated in opposite directions, substantially frusto-conical cutters carried at the center of the facing sides of said gears and provided with radial slots, the edges of said slots in the apices of the cutter converging toward the center of the cutter and 5 being sharpened to form cutting edges, means adjustably connecting said cutters to said gears, the apices of said cutters adapted for engagement to maintain said beveled gears in proper spaced relation.

21. In combination with an apparatus of the character described, a shaft having a toothed wheel mounted thereon, a pivotally supported ratchet lever provided with a pawl engageable with said toothed wheel, a second mentioned lever mounted on the shaft, a timing gearing including a coupling rod joined to the said second mentioned lever, a tie timing regulator including a lock lever, a star wheel supported by the frame and engageable with the lock lever, and means pivotally mounted on the said second mentioned lever and adapted to releasably engage a portion of the said tie timing mechanism to permit rotation of the said star wheel when the said lock lever is released.
22. In combination with an apparatus of the character described, a ratchet wheel, a shaft supporting said ratchet wheel, a ratchet lever engageable with the said ratchet wheel, means to move the said ratchet lever for turning the said wheel, and means to hold the said ratchet lever in a predetermined position after moving the said wheel.
23. In combination with an apparatus of the character described, a shaft having a ratchet wheel mounted thereon, a pivotally mounted ratchet lever engageable with the wheel to move the latter when the ratchet lever is actuated, means connected to the ratchet lever to move the latter, means for holding the said ratchet lever in a predetermined position after moving the said wheel, and means to release the said last mentioned means.
24. In combination with an apparatus of the character described, a ratchet wheel, a shaft supporting the wheel and provided with a lever having one end connected to the shaft, a ratchet lever engageable with said ratchet wheel, means for moving said first named lever, a pawl connected to said first named lever and engageable with the said ratchet wheel for actuating the latter when said means is operated, and means for holding said ratchet lever in a predetermined position after moving said wheel.
25. In combination with an apparatus of the character described, a ratchet wheel, a shaft supporting the wheel, a lever having

- one end connected to the shaft, a ratchet lever engageable with said ratchet wheel, means for moving said first named lever, a pawl connected to said first named lever and engageable with said ratchet wheel for actuating the latter when said means is operated, a latch lever suspended above said first named lever and releasably engaged with a portion of said ratchet lever.
26. In combination with an apparatus of the character described, a ratchet wheel, a shaft supporting the wheel, a lever having one end connected to the shaft, a ratchet lever engageable with said ratchet wheel, means for moving said first mentioned lever, a pawl connected to said first mentioned lever and engageable with said ratchet wheel for actuating the latter when the said means is operated, a latch lever suspended above said first mentioned lever and releasably engaged with a portion of said ratchet lever, said lock lever having means for releasing said lock lever from engagement with said ratchet lever.
27. In an apparatus of the character described, the combination with a ratchet wheel, means for moving and locking said ratchet wheel, a lock lever engageable with said means, a star wheel rotatably mounted and engageable with said lock lever to release the same when said wheel is rotated, and means to impart rotary movement to said star wheel.
28. In combination with an apparatus of the character described, a ratchet wheel, means for moving and locking said ratchet wheel, a locking lever releasably engageable with said means, a shaft having a star wheel mounted thereon and adapted for engagement with said lever to move the lever into released position, a toothed wheel mounted on said shaft, and means engageable with said toothed wheel to impart movement to the latter at regular intervals.
29. In combination with an apparatus of the character described, a ratchet wheel, means for moving and locking said ratchet wheel, a locking lever releasably engageable with said means, a shaft having a star wheel mounted thereon and adapted for engagement with said lever to move the lever into released position, a toothed wheel mounted on said shaft, means engageable with said toothed wheel to impart movement to the latter at regular intervals, and means to prevent rotation of said toothed wheel in the opposite direction.
30. In combination with an apparatus of the character described, a ratchet wheel, a lever, a shaft supporting said ratchet wheel and said lever, means for imparting movement to said lever, and means for holding said ratchet wheel against movement when said lever has been moved to a predetermined position.

31. In an apparatus of the character described, the combination of a ratchet wheel, a shaft supporting the ratchet wheel, a flanged wheel mounted on the shaft, a 5 sprocket engaging the flanged wheel, a disk mounted upon said flanged wheel and fixed to said sprocket, and means pivotally mounted between said sprocket and disk and engageable with said flanged wheel to simultaneously move the wheel with said sprocket when the shaft is rotated.

32. In an apparatus of the character described, the combination of a ratchet wheel, a shaft supporting the ratchet wheel, a flanged wheel mounted on the shaft, a sprocket engaging the flanged wheel, a disk mounted upon the flanged wheel and fixed to said sprocket, means pivotally mounted between said sprocket and disk and engageable with said flanged wheel to simultaneously move the wheel and sprocket when the shaft is rotated, and means carried by the disk and engageable with the ratchet wheel to impart movement to the ratchet wheel when said disk is rotated.

33. In combination with an apparatus of the character described, a shaft, a ratchet wheel mounted on the shaft, a flanged wheel also mounted on the shaft, means engageable with the flanged wheel to impart movement to the ratchet wheel when the flanged wheel is rotated, and means to actuate said first mentioned means at predetermined regular intervals.

35 34. In combination with an apparatus of the character described, a shaft, a ratchet wheel mounted on the shaft, a flanged wheel also mounted on the shaft, means engageable with the flanged wheel to impart movement to the ratchet wheel when the flanged wheel is rotated, means to actuate said first mentioned means at predetermined regular intervals, said means including segmental gears, shafting supporting the gears, and levers connecting said shafting with said first mentioned shaft.

35. In combination with an apparatus of the character described, a shaft, a ratchet wheel mounted on the shaft, a flanged wheel 50 also mounted on the shaft, means engageable with the flanged wheel to impart movement to the ratchet wheel when the flanged wheel is rotated, means to actuate said first mentioned means at predetermined regular intervals, said means including segmental gears, shafting supporting the gears, levers connecting said shafting with said first mentioned shaft, said segmental gears having bearings for supporting the gears, a frame supporting said bearings, and rack bars engageable with certain of said segmental gears to impart movement to the gears at predetermined intervals. 55 60

65 36. In combination with an apparatus of

the character described, a shaft, a ratchet wheel mounted on the shaft, a flanged wheel also mounted on the shaft, means engageable with the flanged wheel to impart movement to the ratchet wheel when the flanged wheel is rotated, means to actuate said first mentioned means at predetermined regular intervals, said means including segmental gears, shafting supporting the gears, lever connecting said shafting with said first mentioned shaft, said segmental gears having bearings for supporting the gears, a frame supporting said bearings, rack bars engageable with certain of said segmental gears to impart movement to the gears at predetermined intervals, and means to regulate the duration of said intervals. 70 75 80

37. In combination with an apparatus of the character described, a compressor head, guide members carried by the compressor head, a pair of rack bars, pawls releasably carried by the guide members and engageable with the rack bars to actuate the rack bars when said compressor head is reciprocated, and means to releasably hold the said pawls above the rack bars. 90

38. In a baling apparatus, the combination with a compression chamber, of means for preventing back pressure of material within the chamber including a catch member hingedly connected to the top of the baling chamber, and a plurality of guard members pivotally carried by said catch member, said guard members having a plurality of teeth on their under surfaces inclining in the direction of movement of material being compressed. 95 100

39. In a baling apparatus, the combination, with a compression chamber, of means for preventing back pressure of material within the chamber including a catch member hingedly connected to the top of the baling chamber, a plurality of guard members pivotally carried by said catch member, said guard members having teeth on their under surfaces inclining in the direction of movement of material being compressed, spiral springs connected to said guard members and normally urging them upwardly, and clutch springs engaging said catch element to maintain said guard members in an operative position. 105 110 115

40. In a baling apparatus, a compression chamber, having a top, side walls and a bottom, said top comprising a rigid section and a hinged section, means for adjusting the position of said hinged section, means for preventing back pressure of material within said chamber including a cap member hingededly connected to the rigid section of said top, a plurality of guard members pivotally carried by said cap member, said guard members having teeth on their under surfaces inclining in the direction of movement of the material being compressed, 120 125 130

spiral springs connected to said guard members and normally urging them upwardly, and clutch springs engaging said catch element to maintain said guard members in an operative position.

41. In a baling apparatus, a compression chamber having a top, side walls and a bottom, said side walls including pressure cap members at the outer end of the chamber, retaining strips connected to the cap member, threaded studs carried by the pressure cap members, ratchets provided with threaded bores mounted upon said studs for moving said pressure cap members toward or away from each other upon rotation of the ratchets, means for rotating said ratchets, and means for locking said ratchets against movement.

42. In a baling apparatus, the combina-

tion of a frame having a pair of carriages 20 mounted therein and adapted for lateral movement toward and away from each other, a plurality of beveled gears carried by one of the carriages and arranged in opposed pairs, each of said gears having a 25 radial slot, pinions mounted on said last named carriages and meshing one with each pair of gears to rotate the gears of each pair in opposite directions, means mounted on the frame and connected to the carriages for 30 moving them toward and away from each other, fingers carried by one of the carriages, the centers of the said gears, and the ends of said fingers being adapted for registration when the carriages are moved toward 35 each other.

LEE R. LOWTHER.
